DES. 2068

Sargent & Co. of the same place.

Letters Patent No. 2068. Dated May 16, 1865.

Design for a Coffin Handle.

The schedule referred to in the Letters Patent and making part of the same.

To all whom it may concern:

Be it known that I, Clark Ludwig Schreyer, of New Haven, in the County of Hartford and State of Connecticut, have invented a new and useful design of Handle for Burial Cases, Coffins, &c. and I do hereby declare that the following is a full, clear and exact description thereof, which will enable those skilled in the art to make and use the same, reference being had to the accompanying drawings forming part of this specification.

In the accompanying plate of drawings my new design is represented by a front view of the same and consists in making the handle a, in a semi-circular shape of an suitable metal or material, either plated or not with silver or gold as may be desired, and terminating at each end in a short straight shape, turning in bearing of two circular staples c, c, of plates d, d, fastened by screws or other proper devices to and upon the end or side pieces of the coffin or burial casket.

The handle a, is ornamented with twisted cords d, d, alternating passing over and under the same for its entire length, forming a series of loops f, f, but made into a knot or bow g, at the centre of the handle. These cords can be either attached to the handle c, c, moulded upon the same, in the form described.

The plates d, d, are made with an scalloped edge as shown in the drawings in the centre of each of which is an aperture b, to receive the heads of the screws used for fastening them to the burial casket, and are formed by bending twisted cords l, l, around in the said shape having knots m, which form the staples or bearings for the handle to turn in as described, and

DES. 2068

2. Tassel-shaped cords or as. These cords can be attached together by any proper means or provided in one piece.

Claim as new and desire to secure by letters Patent.

The design for a Handle for Coffins, Burial Cases, Baskets &c. having the general form, shape and configuration herein described and represented in the drawings.
